UNITED STATES PATENT OFFICE.

CHARLES F. QUICK AND GEORGE W. TAMSITT, OF DALLAS, TEXAS.

ELEVATOR RELAY.

Application filed December 27, 1924. Serial No. 758,340.

This invention relates to new and useful improvements in elevator floor signal systems.

The object of the invention is to provide a floor signal system in which means is provided for causing a positive operation and whereby failure of the signal lamp to light is eliminated.

A particular object of the invention resides in a novel form of relay for actuating a gravity contact, whereby an efficient and simple circuit closing switch is provided for each signal lamp.

Another feature of the invention is to provide electrically actuated means for resetting the relays and clearing the lamps.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a circuit diagram of the system,

Fig. 2 is a front elevation of the relay panel,

Fig. 3 is a partial vertical sectional view on the line 3—3 of Fig. 2,

Fig. 4 is a cross sectional view on the line 4—4 of Fig. 2, and

Fig. 5 is a detail of one of the relays showing the dog just after it is released from the hook.

In the drawings the numeral 10 designates a panel upon which a plurality of relays are mounted. This panel may be mounted in a box or case 11, which may be disposed in the pent house, elevator shaft or other convenient place. On each side of the panel are mounted electromagnets 12, one for each floor on each side. In Figs. 2 and 3 five magnets on each side are provided, illustrating five floors, but the number will of course vary with the number of floors in the building. The magnets are superposed. In front of each magnet is pivoted an armature hook 13 upon a screw 14. Each hook has on its side opposite from the magnet a notch 15 at the bottom of which is formed a stud 16. The hook is pivoted at one corner so as to normally swing away from the magnet.

For each hook is provided a dog 17 mounted on a pivot screw 18 and its back bevelled at 19 whereby it is reduced to a substantial point. The point of each dog is undercut to form a finger 20 which engages in the notch 15 on the stud 16. Each finger normally occu-

pies a horizontal position. Below each dog is a contact pin 21. When a magnet is energized it attracts the hook 13 which swings to the magnet thus carrying the stud 16 from under the finger 20. This permits the dog 17 to swing down and rest upon the contact pin 21, as is shown at a in Fig. 2. The lower end of each hook has a bevelled edge 22 and when the magnet is de-energized the hook is freed and swings outward so that its bevelled edge 22 rides up the back 19 and holds the dog on the pin.

For restoring the parts to their normal position a resetting device is provided for each row of magnets. Each device consists of a vertical rod 23 mounted to slide in angular brackets 24 and 25 mounted on the panel 10. The rod has a collar 26 above the bracket 25 and a collar 27 below the bracket. Normally the collar 26 supports the rod on the bracket 25; while the collar 27 limits the upward movement of the rod. Above each rod is an electromagnet 28 supported by a bracket 29. Each rod has a pin 30 under each dog. Thus when one of the magnets 28 is energized it pulls the rod upwardly, whereby each pin 30 engages a dog 17 and swings it up so that the finger 20 rides into the notch 15 and engages over the stud 16. When the rod is freed it drops to its normal position. The bevelled edges play an important part and the positive action of the hooks and dogs is of great advantage.

In Fig. 1 is shown a circuit diagram showing push buttons A and B located at each of the five floors. A plurality of signal lights A' and B' are shown and are supposed to be mounted in the elevator car. The buttons A are pressed by passengers desiring to go up while the buttons B are pressed by the passengers desiring to go down. A main circuit wire C supplies current to one side of each button by a branch wire C'; also to one side of each lamp by branch wires C''. From each up button a wire A'' leads to one of the magnets 12, the top wire leading to the top magnet on the left hand side. From each down button B a wire B'' leads to a magnet 12 on the right hand side of the panel, the top wire 100 leading to the top magnet and so on.

The signal lamps A' are for the "up" signals; while the lamps B' are for the "down" signals. A wire A''' leads from each lamp A' to a contact pin 21 on the left hand side of the panel 10. A wire B''' leads from each lamp B' to one of the pins 21 on the right hand side.

of the panel. A second main circuit wire D has branches D¹ connected with each magnet and other branches D² connected with each dog 17. At the bottom of the signal lamps are switch buttons, E and F respectively, each having one side connected with the circuit wire C by branches C³. From the button E a wire E' leads to the left hand magnet 28 which is connected with the wire D by a branch D³. 10 A wire F' leads from the button F to the right hand magnet 28 which is connected to wire D by a wire D⁴.

A passenger on the second floor wishing to go up pushes the up button A. A signal lamp box is arranged in each elevator car connected in multiple with the relays of the panel 10. Current from the wire C passes through the button A on the second floor over wire C¹, thence by wire A² to the magnet 12 on the 20 left hand side of the panel 10. The second magnet from the bottom is thus energized, the circuit being completed over wires D¹ and D. When the magnet is energized the hook 13 is swung, whereby the dog 17 is dropped on the 25 pin 21. The circuit to the magnet is broken when the button is released. When the dog drops onto the pin, the circuit is closed from wire C over wire C² to the up lamp A' marked 2, thence over wire A³ to the pin 21 and thence 30 from the dog 17 over wires D², D' and D. The signal light will be illuminated at each signal box.

If an operator desires to clear the signal or extinguish the lamp or lamps he pushes the button E which closes the circuit from wire C over wires C³, E' to the left hand magnet 28 and thence over wires D³ and D. This energizes the magnet 28 which raises the left hand 35 rod, 23, causing its pins 30 to restore the dogs 40 17, and hooks 13 to their normal position.

If a passenger on the fourth floor desires to go down he presses the button B which closes the circuit from wire C over wires C² and B² to the right hand magnet 12 at "4" and thence 45 over wires D¹ and D. This energizes the magnet which attracts the hook 13 and drops the dog 17 into the pin 21. The circuit is thus closed from wire C over wire C² through lamp B at "4" and thence over wire B³ to the pin 50 21 and thence through the dog 17 and the wires D², D¹ and D.

Various changes in the plurality and location of the parts as well as structural changes may be made within the scope of the 55 appended claims.

What we claim, is:

1. In an elevator signal system, a relay for a control panel assemblage comprising a magnet, an armature hook pivoted adjacent the 60 magnet and having a stud upon its outer face and a holding face extending downward from the stud, a dog forming a circuit contact and pivoted opposite the end of the magnet and having at its free end a finger engaging the 65 stud and an upper surface to engage the hold-

ing face of the hook when released from the magnet, and a supporting contact below the dog in the path thereof.

2. In an elevator signal system, a relay for a control panel assemblage comprising a magnet, an armature hook pivoted adjacent the magnet and having a stud upon its outer face and a depending inclined holding face, a dog forming a circuit contact pivoted opposite the end of the magnet and having at its free end a finger engaging the stud and an inclined upper surface to support the holding face of the hook when released from the magnet, a circuit contact disposed beneath the dog to retain the same, a resetting magnet, and an armature therefor having means to engage the free end of the dog to raise it from the last mentioned circuit contact into engagement with the stud.

3. In an elevator signal system, a control panel assemblage consisting of a plurality of aligned relays each comprising a magnet, a hook pivoted adjacent each magnet and having a supporting face, a circuit contact dog pivoted with its free end disposed to engage 85 said face, a circuit contact below each dog to support the same when released by the hook, a vertical armature rod having pins to simultaneously engage the under face of said dogs, and a resetting magnet aligned with said 90 rod to lift the dogs from the contact into engagement with the hook.

4. In an elevator signal system, an electromagnet, a cooperating armature hook having a notch and stud and a bevelled holding-edge 100 beneath said stud, a pivoted dog forming a circuit contact and having a reduced finger to engage the notch of the hook and a bevelled upper edge to receive the bevelled edge of the hook when the dog is released, a circuit 105 contact pin disposed to support said dog when released and engaged by said holding edge, a vertical resetting rod having a pin for engaging the dog, means for limiting the movement of said rod, and an electro-magnet disposed to attract and raise the rod.

5. In a control panel for an elevator floor signal system, a plurality of aligned relays, each comprising a magnet, a pivoted gravitational contact device, a circuit terminal disposed to support said device, an armature member for the magnet pivoted to gravitate toward said contact device and having a seat for supporting the device in elevated position and a holding surface at its lower portion disposed to rest upon and automatically retain the device when lowered into contact with said terminal, and an electrically reciprocated member having means disposed beneath each contact device to simultaneously engage and reset the same.

In testimony whereof we affix our signatures.

CHARLES F. QUICK.
GEORGE W. TAMSITT.
